UNITED STATES PATENT OFFICE.

ABRAHAM FISHER, OF NEW YORK, N. Y.

SHIRT.

1,264,046.

Specification of Letters Patent.

Patented Apr. 23, 1918.

Application filed September 20, 1917. Serial No. 192,343.

To all whom it may concern:

Be it known that I, ABRAHAM FISHER, a citizen of the United States, and a resident of the city of New York, borough of Bronx, 5 in the county of Bronx and State of New York, have invented a new and Improved Shirt, of which the following is a full, clear, and exact description.

My invention relates to convertible shirts. 10 The object of the invention is to provide a shirt adapted to present a rolling collar or an ordinary collar band.

This application is an improvement over the shirt disclosed in my application No. 15 147,063, filed February 7, 1917, allowed August 2, 1917.

The invention is characterized from the shirt disclosed in the above application by the elimination of the V-shaped notch in the 20 folding band and by the elimination of the flaps on the inner side of the shirt.

In the accompanying drawings, forming part of the application, similar characters of reference indicate corresponding parts in 25 all the views.

Figure 1 is a front elevation of the shirt when worn with a rolling collar;

Fig. 2 is a similar view of the shirt when worn to present a shirt band to receive a detachable collar;

Fig. 3 is an elevation of the front collar blank shown as it appears secured to the shirt;

Fig. 4 is an elevation of the rear collar blank shown secured to the shirt;

Fig. 5 is a perspective view of the shirt collar when the collar blanks are folded outwardly to present a collar band doubled outwardly to receive a detachable collar;

Fig. 6 is a similar view showing the collar band doubled inwardly;

Fig. 7 is a cross section on line 7—7, Fig. 5;

Fig. 8 is a cross section on line 8—8, Fig. 45 6; and

Fig. 9 is an elevation of the blanks forming the collar, showing the manner in which the lining for the collar is formed. This figure also shows the blanks slightly modified from those illustrated in the other figures.

Referring to the drawings, the neck band 9 is formed of an outer blank 10 of suitable shape and an inner blank 11 in the shape of 55 an arch, the upper part of said blank 11 being similar in shape to the outer blank 10.

It may be trapezoidal, as shown in Figs. 1 to 8 inclusive, or rectangular, as shown in Fig. 9. The wider edge of the outer blank is secured through its entire length to the shirt material at the neck opening with the exception of the middle portion thereof which gives access to the rear buttonhole 12. The inner blank is secured only through the straight portion of its inner edge to the material of the shirt at the neck opening, thereby leaving the flap portions 13 on the inner edge unsecured, while the outer edge of said flap portions is secured to the material of the shirt at the front opening of the shirt. The two blanks are secured to each other at the outer edges.

The width of the blanks 10 and 11 is sufficient to form a rolling collar on the shirt. In consequence, it is necessary to double 75 the blank when the shirt is to be worn with a detachable collar. To render the doubled-up collar sufficiently rigid I provide reinforcing strips 14 which have a width less than half the width of the blanks 10 and 11, 80 that is, half the height of the collar, and which are separated at the proximate edges by a gap 14', which gap is formed in the place of the blank where the same folds to form the collar. Preferably the edges at 85 the gap are left unsecured to the blank. The blanks 10 and 11 can be folded outwardly, as shown in Fig. 5, or inwardly, as shown in Fig. 6. When folding it outwardly, a portion of the inner blank will 90 fold outwardly (see Fig. 2). The sloping edges 15 of the blank clear the buttonholes 16 provided near the wider portions of the blanks 10 and 11.

When the collar band is folded outwardly, as shown in Figs. 2, 5 and 7, the buttonholes 12 will be covered by the outer section of the collar band; and for this purpose it is provided with a buttonhole 17 which is adapted to register with the buttonhole 12 so that a collar button 18 can pass from beyond the inner blank 11 out through the folded section of the inner blank. On the other hand, when the collar band is folded inwardly, as shown in Figs. 6 and 8, then the buttonhole 17 will be disposed within the blank 11. When the collar band is folded inwardly, the sloping edges 15 of the blanks clear the buttonhole 16.

When the shirt is to be worn with a rolling collar the blank 11 is folded outwardly,

bringing the blank 10 against the back of the shirt. This will bring the sloping edges 15 substantially parallel with the front opening of the shirt, while the outer edges 5 run diagonally so as to give the shirt the appearance of one having a rolling collar.

From the description it will be seen that a shirt made in the manner described can be easily and quickly transformed from one 10 having a rolling collar to one with a neckband for a detachable collar, stiff or soft as the case may be.

I claim:

1. In a shirt of the class described, a neckband formed of a rear or outer blank and an arch-shaped inner blank the upper portion of which is similar in shape to the rear or outer blank, said blanks being secured to each other at their outer edges, the inner

blank being also secured to the shirt at the 20 front opening, and reinforcing strips between said blanks having a gap running longitudinally of said blanks and which facilitates the folding of said blanks substantially as and for the purpose set forth. 25

2. In a shirt of the class described, a neckband formed of a rear or outer blank and an arch-shaped inner blank the upper portion of which is shaped similarly to the rear or outer blank, said blanks having button holes at the front, the upper edges of 30 said blank tapering toward the side edges so that when said neckband is folded to receive a detachable collar the tapering upper edge of the band will present a clearance 35 at the button holes.

ABRAHAM FISHER.
